UNITED STATES PATENT OFFICE.

JAMES WILLIS, OF ROSENDALE BOURNEMOUTH, COUNTY OF HANTS,
ENGLAND.

UMBRELLA AND PARASOL.

SPECIFICATION forming part of Letters Patent No. 319,767, dated June 9, 1885.

Application filed November 27, 1883. (No model.) Patented in England May 1, 1883, No. 2,202; in France October 30, 1883, No. 158,325; in Belgium November 12, 1883, No. 63,190, and in Germany November 15, 1883, No. 28,805.

To all whom it may concern:

Be it known that I, JAMES WILLIS, a subject of the Queen of Great Britain, residing at Rosendale Bournemouth, in the county of Hants, England, have invented certain new and useful Improvements in Umbrellas and Parasols, (for which I have received Letters Patent in Great Britain, No. 2,202, dated May 1, 1883; in France, No. 158,325, dated October 30, 1883; in Belgium, No. 63,190, dated November 12, 1883, and in Germany, No. 28,805, dated November 15, 1883,) of which the following is a specification.

This invention has for its object improvements in umbrellas and parasols, and relates in the first place to the joints by which the ribs and the stretchers are connected.

Figure 1 of the annexed drawings is a side elevation of a joint connecting a rib of an umbrella with a stretcher. Fig. 2 is a longitudinal section of the same. Figs. 3 show the parts separately. Figs. 4, 5, and 6 represent a joint connecting the rib of an umbrella or parasol with a three-forked stretcher in which a spring of arched form is employed. Figs. 7 represent the flattened end of one of the ribs. Figs. 8 show the stretcher which I employ together with the rib shown by Figs. 7. Fig. 9 shows the positions of these parts when the umbrella or parasol is closed. Figs. 10 show the end of a rib prepared for the formation of the eye. Fig. 11 shows another part used in making the eye. Figs. 12 show these parts combined and the eye complete. Figs. 13 represent a pair of dies employed in forming the tip. Figs. 14 represent another pair of dies subsequently employed. Fig. 15 shows the finished form of tip.

In accordance with my invention I make the spring-joints connecting the ribs and stretchers as follows: I use a trough-form rib and a three-forked stretcher. I secure the spring in the hollow of the trough in such a position that it presses on the middle prong of the stretcher-fork beyond the point of pivotal attachment of the stretcher to the rib. The prong is made square-cornered and with flat or parallel opposite edges, and the spring acting against these causes the stretcher to close

against and open away from the rib as a spring-knife opens and closes. Figs. 1, 2, and 3 show a spring-joint of this construction.

A is a portion of the rib. B is a git fixed upon the rib. C is the three-fork stretcher. D is the spring attached to the rib. D' D' are two side projections upon the spring, which rest upon the edges of the trough-rib. D' is a short tail or heel projection, which is received into the interior of the trough and fixed there by nipping together the two sides. The square end of the central prong of the fork stretcher is clearly seen in the figures. The free end of the spring D bearing upon it tends, as the umbrella is closing, to press the tips of the ribs inward toward the stick; also, as an additional advantage of this construction, as the umbrella opens the spring tends to move the runner upward upon the stick and to retain it independently of any catch. This arrangement is applicable either to the lock-rib frame, where, as is shown in the drawings, the rib is received into the hollow of a trough-form stretcher, or to the ordinary paragon form of stretcher.

In place of the above construction, I in some cases place into the trough or hollow of the rib an arched spring, the central part of which is made to bear against the end of the central prong of the three-fork stretcher, while the ends of the spring rest on the bottom of the trough; and in order to prevent the spring from moving endwise I extend the middle bit or git along the sides of the rib and form it at its ends with pieces to be bent over into the interior of the rib and form stops to prevent the spring from moving endwise out of its place. Figs. 4, 5, and 6 show this way in which the spring-joint may be made. As in the former figures, A is a portion of the rib. It has a git, A', upon it, which, in this case, is long, so that its two ends (which are turned inward into the interior of the trough) serve as stops to keep the spring D in its place.

The three-pronged stretcher C is somewhat differently formed from that in the figures previously described. The spring, as before, holds the tips of the ribs inward toward the stick when the umbrella or parasol is closed,

and holds the runner up when the umbrella or parasol is opened. The same construction is applicable where the end of the stretcher is single, as it commonly is in parasols and small 5 umbrellas.

It should be noticed that the spring D operates upon the end of the stretcher, whether the stretcher be forked or not, beyond the point of pivotal attachment of the stretcher 10 to the rib, and not elsewhere, with a tendency to hold the rib and stretcher close together when the umbrella is closed.

Another part of my invention relates to umbrellas and parasols having what are known 15 as "lock-rib" frames, or frames in which the stretchers are of trough form, and when the frame is closed the ribs are received into the stretchers. To reduce the thickness of the umbrella or parasol, I use ribs flattened or 20 spread at the ends, and I so form the trough-stretchers as to receive these flattened ends and permit them to lie against the runner-notch. Figs. 7, 8, and 9 show this improvement in the frame. It is of trough-like form, 25 and adapted to receive the rib within it, as usual in a lock-rib frame; but its form at the end which is jointed to the runner is novel. Here the trough of the stretcher is opened out 30 and the sides are reduced in height to enable the stretcher to receive within it that part of the flattened end of the rib which comes against it, and to allow the flattened part of the rib to rest against the runner-notch. The runner is marked E, and a portion of the stick is seen 35 at F.

It will be seen the flattened portion of the rib comes in contact with the runner-notch, and it is permitted to do so by the form which has been given to the end of the stretcher.

40 Another part of my invention relates to a novel manner of forming the eye, by which the cover is sewed to the tip of the rib. It is usual to form this eye in such manner that it projects on the inner side of the rib, an arrangement which is open to objections, one of which is that the eye rubs against and chafes the stick, and another that the fabric has to be drawn around the rib to the eye, which throws an undue strain on the part sewed and 45 causes the stitches to catch only the single fabric instead of the double fabric at the seam. By my invention I produce on a trough-rib, a central eye passing through the end of the rib, which is closed to a cylindrical form. 50 For this purpose the end of the rib is first notched, as is represented at H H in Figs. 10. A piece of straight or undoubled wire, instead of the heretofore-employed doubled or looped wire, is formed, as shown in Fig. 11, 55 with a half-eye or semicircular bend intermediate its ends, and is laid within it, and the sides of the trough-rib are bent inward to embrace the wire, as seen in Figs. 12. The eye is enlarged by means of a smooth taper punch.

Another part of my invention consists in 65 making the globular ends in which the ribs terminate to project to the front outward from the stick. The way in which I prefer to effect this is as follows: I finish the tip first with a globular head in the usual way, the said head 70 projecting equally to the back and front. Then I place the head between a pair of dies, such as represented at Figs. 13, and these bend the neck of the tip in such manner as to throw the globular end outward. The tip is 75 then stamped on its side between tools shown by Figs. 14, and these bring it to the finished form represented at Fig. 15 and remove any roughness which may have been left by the 80 previous tools.

Two objects are gained by causing the globular heads on the tips to project to the front. They are thereby prevented from coming into contact with the stick, and the stick is not injured, and the projection of the globular heads 85 protects to some extent the stitching and parts of the fabric which are sewed to the tips, parts which in the use of the umbrella ordinarily wear rapidly and render the umbrella unsightly and partly unserviceable. 90

Having thus described the nature of my said invention and the manner of performing the same, I would have it understood that I claim—

1. The combination of the rib, the stretcher pivoted thereto, and the spring operating upon the end of the stretcher beyond its point of pivotal attachment to the rib, and not elsewhere, with a tendency to hold the rib and stretcher close together when the umbrella is closed, substantially as set forth. 100

2. The combination of the rib, the stretcher pivoted thereto, and the double-acting spring secured to the rib and operating upon the end of the stretcher beyond its point of pivotal attachment to the rib, and not elsewhere, with a tendency to hold the rib and stretcher close together when the umbrella is closed and to 105 keep them apart when the umbrella is open, these members being constructed substantially as set forth.

3. The combination of the trough-like rib, the spring D, having the side projections, D' D', resting upon the rib, and the tail D'', received into the trough of the rib and fixed there by nipping together the rib sides, substantially as set forth. 115

4. The combination, in a lock-rib frame, of the ribs flattened at their outer ends with trough-stretchers shaped to receive them and admitting of the flattened portion of the rib 120 resting against the notch of the runner, as and for the purpose set forth.

JAMES WILLIS.
